METHOD AND APPARATUS FOR MAKING
FINED TUBINGErnest Bruegger, Massillon, Ohio, assignor to The
Griscom-Russell Company, New York, N. Y.,
a corporation of Delaware

Application April 17, 1945, Serial No. 588,800

13 Claims. (Cl. 153—54)

1

This invention relates to finned tubing, and more particularly concerns an improved method for making finned tubes of non-circular section and an improved apparatus by means of which the method may be performed.

Many forms of apparatus for transferring heat between fluids or other materials employ as their essential heat transfer elements tubes carrying fins on their outer surfaces. In one well known construction, the fin comprises a flat metallic strip or ribbon extending edgewise around the tube and helically along its length with the inner edge of the strip on the tube surface. The helical fin may comprise an element separate from the tube which is wound edgewise about the tube and suitably secured thereto along the inner edge of the strip, or the fin may be formed integral with the tube.

In some cases, it is desirable to provide a finned tube of non-circular section. In particular, a finned tube of elliptical, oval or flattened section presents certain advantages. With such a tube, fluid flowing transversely thereof remains in heat exchanging contact therewith and with the fin structure thereon for longer periods than with circular section tubes, and a larger number of tubes of a given cross sectional area may be disposed side by side across a duct or container of a given size.

It is the object of the present invention to provide an improved method for making finned tubes of non-circular and preferably elliptical, oval or flattened section. More specifically, the invention contemplates a method by means of which a circular section helically finned tube of the type described is shaped to an elliptical, flattened or otherwise transversely elongated or non-circular section.

Another object of the invention is to provide improved apparatus by means of which a helically finned tube of non-circular and preferably elliptical or flattened section may be produced. More particularly, the invention contemplates apparatus for progressively shaping or bending a circular section helically finned tube to elliptical or other non-circular cross sectional form, without loosening, warping or otherwise adversely affecting the fin or its attachment to the tube.

Other objects of the invention include the provision of a method and apparatus capable of rapidly and economically shaping circular section helically finned tubes to flattened, elliptical or other non-circular section without injury to the tube or the fin structure.

In general, the method of the invention is car-

2

ried out by employing a finned tube of circular section having a helical fin of the flat edgewise protruding strip or ribbon type on the tube surface, and progressively compressing the tube and the fin transversely of the tube axis along portions of the fin and tube that progress circumferentially of the structure in a helical path, the amount of such compression being varied in timed relation to the progress thereof circumferentially of the tube. The amount of transverse compression may be varied between maximum and minimum limits as the compression progresses through each successive quarter of the circumference of the tube in order to produce a finned tube of elliptical or flattened section. The fin is preferably supported against bending or warping movement lengthwise of the tube during the progressive compression of the tube and the fin.

The apparatus of the invention includes means for supporting a helically finned tube while advancing it relative to one or more pairs of compressing rollers or equivalent means that simultaneously engage the tube and fin at diametrically opposite points, and that progress circumferentially of the tube and helically along its length, together with means for successively moving the rollers of each pair toward and away from each other in timed relation to the relative movement of the rollers around the tube. The rollers are preferably tapered to progressively compress the tube and its fin in relatively small increments, and are also preferably slotted so as to simultaneously engage the tube surface and the fin edge and to support the fin against movement lengthwise of the tube.

In describing the invention in detail, reference will be made to the accompanying drawings in which a typical embodiment of apparatus involving the invention and capable of carrying out the improved method has been illustrated. In the drawings:

Fig. 1 is a partial front elevation of apparatus embodying the invention;

Fig. 2 is a sectional elevation of the tube shaping apparatus on an enlarged scale;

Fig. 3 is an end elevation of the tube and fin compressing apparatus taken along the line 3—3 of Fig. 2 and viewed in the direction of the arrows;

Fig. 4 is an end elevation of the apparatus showing the tube supporting mechanism and taken along the line 4—4 of Fig. 2 and viewed in the direction of the arrows;

Fig. 5 is an enlarged view, partly in section, showing one of the pairs of tube and fin com-

pressing rollers at their positions of maximum transverse compression;

Fig. 6 is an enlarged view similar to Fig. 5 showing the pair of rollers at their position of minimum transverse compression;

Figs. 7 and 8 are respectively cross sectional views of finned tubes before and after being shaped to elliptical or flattened section in accordance with my improved method;

Fig. 9 is a longitudinal section of a tube carrying an integral helical fin; and

Fig. 10 is a longitudinal section of a tube carrying a helical fin formed separately from the tube.

Referring to the drawings and particularly to Figs. 1 and 2, the illustrated embodiment of my improved apparatus includes a fixed tubular support 11 of appropriate length carried by suitable columns 12 secured to a base 13. The tubular support 11 is preferably somewhat longer than the longest finned tube to be shaped by the apparatus. A keyway 14 extends longitudinally throughout the bore of the support 11, and a key 15 fixed to an expansion bushing 16 which may be secured to a tube 17 rides freely in the keyway 14.

The tube 17 is the finned tube which is to be shaped from circular to elliptical or flattened section. In the illustrated embodiment, this tube carries a helical fin 18 on its outer surface, the fin being in the form of a thin continuous strip or ribbon extending radially outward from the tube surface and circumferentially of the tube in a helical path of equally spaced turns. The fin may be formed integrally with the tube, and such a construction has been illustrated in Fig. 9 where the tube 17 carries an integral helical fin 18. A more usual construction is illustrated in Fig. 10 where the fin 18 is a separate ribbon and is secured to the tube 17 along its inner edge by embedding the fin edge in the tube metal in a manner known in the art. Other known forms of attachment of the fin to the tube may be employed.

The tubular support 11 terminates in a circular flange 19, and a rotary head 20 is journaled on the support 11 adjacent its flanged end. As shown, the head 20 is cylindrical and turns on anti-friction bearings 21 disposed between it and the support 11. An end plate 22 encloses the rearward end of the bearing space, and a sealing ring 23 may be provided at the inner edge of the end plate 22 for engagement with the outer surface of the support 11. A driving gear 24 is suitably fixed to the head 20 and is driven by a pinion 25 secured to a drive shaft 26 carried in journals including the journal 27 fixed to the base 13. The shaft 26 may be driven by any suitable means such as a motor, not shown. A bed 28 of a length at least as great as that of the longest tube to be treated is fixed to the base 13 beyond the end of the rotary head 20. A carriage 29 is slidably mounted on the bed 28 and the shaft 26 has a threaded portion 30 engaging a lug 31 on the carriage 29. With this arrangement, rotation of the shaft moves the carriage 29 outward from the head 20 along the bed 28 in timed relation to the rate of rotation of the head. The outer end of the tube 17 is fixed to the sliding carriage 29 by any suitable means such as the expansion bushing 63.

The outer end of the rotary head 20 carries a plurality of pairs of radially movable compressing rollers 32, 33 and 34, 35. The rollers are of identical construction, and the rollers of each pair are arranged to move in diametrically opposite direc-

tions radially of the head. As shown in Figs. 5 and 6, each of these rollers comprises a plurality of circular fin-like ridges 36 separated by valleys 37, and the rollers are tapered so that the diameters of the successive ridges 36 and valleys 37 increase outwardly from the head 20. The ridges 36 have a thickness substantially equal to the space between adjacent turns of the helical fin 18 on the tube 17 to be shaped, and the depth of the valleys 37 is substantially equal to the height of the fin strip above the tube surface. The width of each of the valleys 37 is substantially equal to the thickness of the fin strip 18.

Any suitable means may be provided for slidably supporting the rollers 32, 33, 34 and 35 on the end of the head 20. In the disclosed embodiment, each of these rollers is journaled by means of a shaft 38 in a bifurcated bracket 39 secured by the bolts 40 to the inner face plate 41 of a sliding carriage 42. The carriage 42 includes a plate 43 which is slidably supported between overhanging track bars 44 fixed to an outer face plate 45 on the rotary head 20. The face plate 45 carries a central pilot bushing 46 which closely surrounds and supports the finned tube under treatment, and a spring 47 is disposed between the outer surface of the pilot bushing and the inner end of each carriage plate 43. With this arrangement, each of the carriages 42 is biased to move radially outward from the axis of rotation of the head 20. A cam follower roller 48 is rotatably journaled between arms 49 at the outer end of each bracket 42.

A stationary internal cam 65 surrounds the roller carrying brackets 42 and is engaged by the cam follower rollers 48. The cam 65 is suitably secured to a circular cam housing 66 carried by a support 67 secured to the base 13. As shown in Fig. 3, the inner edge of the cam 65 is elliptical, having its long axis substantially horizontal and its short axis substantially vertical. With this arrangement, as the head 20 rotates, the compression rollers of the pairs 32-33 and 34-35, are moved between extreme closely spaced and widely separated positions during each quarter of a revolution of the head 20. These extreme positions of the pair of rollers 32, 33 are respectively illustrated in Figs. 5 and 6.

The openings in the face plate 41 of each carriage 42 through which the bolts 40 pass are considerably larger than the bolts so that the angle between the axis of rotation of the roller 32 and the axis of the tube 17 may be adjusted. By such adjustment, the compression rollers can be set to have the same lead as the helically wound fin 18 on the tube 17, whereby the ridges 36 of the compression rollers lie parallel to and between successive turns of the fin 18 as the rollers are carried around the tube 17 by the rotary head 20. The lead of the threads on the threaded portion 30 of the shaft 26 is so related to the ratio between the pinion 25 and the head gear 24 that the sliding carriage 29 is advanced by a distance equal to the spacing of successive turns of the helical fin 18 during each complete revolution of the head 20.

The tube 17 being shaped is preferably supported adjacent the portion thereof engaged by the compression rollers 32, 33, 34 and 35. In the disclosed embodiment, the pilot bushing 46 which fits closely about the outer edge of the tube fin 18 forms one such support. The shaped tube is supported and held against rotation on the other side of the compression rollers by a pair of identical supporting rollers 50 disposed

above and below the tubes, as shown in Figs. 1, 2 and 4. As best shown in Fig. 4, the faces of these rollers 50 are concave so that together they form an elliptical opening through which the flattened finned tube 17 passes. The rollers 50 are carried in journals 51 and 52 which are vertically slideable in frames 53 and 54 mounted on posts 55 and 56 that are suitably secured to the base 13. Upper and lower springs 57 and 58 are provided to bias the journals 51 and 52 of 10 the upper and lower rollers toward each other. Screws 61 and 62 operable by hand wheels 59 and 60 are provided for variably adjusting the force exerted by the springs 57 and 58.

In the operation of the disclosed embodiment of my apparatus in carrying out my improved method, a finned tube such as the tube 17 carrying the helical fin 18 is inserted in the bore of the support 11 and the expansion bushing 16 is secured to the trailing end of the tube. The key 15 on the bushing 16 is inserted in the keyway 14, the leading end of the tube being inserted through the pilot bushing 46. A length of the tube 17 adjacent its leading end preferably carries no fin turns, and this bare leading end is inserted between the compression rollers 32, 33, 34 and 35, is compressed to elliptical shape by rotation of the head 20 and is passed between the supporting rollers 50 and secured by the expansion bushing 63 to the carriage 29. The helical fin 18 on the tube 17 is threaded into the valleys 37 of the compression rollers 32, 33, 34 and 35. Rotation of the head 20 is continued, and the carriage 29 advances, drawing the tube 17 through the head 20. The advancing tube 17 is held against rotation by the engagement of the key 15 in the keyway 14 and by the action of the supporting rollers 50. During the progress of the tube, the diametrically opposite pairs of compression rollers 32, 33, 34 and 35 travel circumferentially around the tube 17 and simultaneously compress it and its fin 18 in progressive stages due to the taper of the compression rollers. The compression is applied transversely of the tube by the pairs of compression rollers and this compression varies circumferentially of the tube between a maximum compression when each pair of oppositely disposed rollers lies in a vertical plane through the tube axis and a minimum compression when each such pair of oppositely disposed rollers lies in a horizontal plane through the tube axis. The tube 17 and its fin 18 are thus shaped from circular to elliptical section in progressive stages as the tube advances. During this shaping, the fin is supported against buckling, bending or other movement longitudinally of the tube by the ridges 36 on the compression rollers which hold the fin therebetween. Since the compressive force is exerted simultaneously and equally on the tube surface and the fin edge, there is no tendency for the tube to separate from the fin during the shaping operation.

In the disclosed embodiment, the cam 65 which governs the compressive movement of the compression rollers is elliptical in form with the result that the non-circular section to which the finned tube is shaped is elliptical. The invention is not limited to this form of cam or finished tube, and it will be apparent that other non-circular sections of finned tube can be obtained 70 by employing suitably shaped cams.

I claim:

1. The method of shaping to non-circular section a circular section tube having a flat fin extending edgewise from its surface along a helical 75

path which comprises simultaneously compressing the tube and the fin transversely of the tube axis along portions thereof that progress circumferentially of the tube and in the helical path of the fin along the tube length while supporting the fin against movement lengthwise of the tube, and varying the amount of such compression in timed relation to the progress of the compression circumferentially of the tube.

2. The method of shaping to elliptical section a circular section tube having a flat fin extending edgewise from its surface along a helical path which comprises simultaneously compressing the tube and the fin transversely of the tube axis along portions thereof that progress circumferentially of the tube and in the helical path of the fin along the tube length, and varying the amount of such compression between maximum and minimum limits as the compression progresses through each successive quarter of the circumference of the tube.

3. The method of shaping to elliptical section a circular section tube having a flat fin extending edgewise from its surface along a helical path which comprises simultaneously compressing the tube and the fin transversely of the tube axis along portions thereof that progress circumferentially of the tube and in the helical path of the fin along the tube length while supporting the fin against movement lengthwise of the tube, and successively increasing the amount of such compression to a maximum limit and decreasing such amount to a minimum limit as the compression advances through each successive quarter of the circumference of the tube.

4. Apparatus for shaping to non-circular section a circular section finned tube having a helical fin extending outwardly from its surface comprising spaced compression means for simultaneously engaging the tube fin and the tube at diametrically opposite points, means for moving said compression means circumferentially relative to the tube and helically along the tube fin and means for moving said compression means toward and away from each other to apply successively increasing and decreasing compression to the tube and the fin during such circumferential movement of said compression means.

5. Apparatus for shaping to non-circular section a circular section finned tube having a helical fin extending outwardly from its surface comprising a pair of spaced compression rollers for simultaneously engaging the tube fin and the tube surface at diametrically opposite points, means for moving said compression rollers circumferentially relative to the tube and helically along the tube fin and means for moving said compression rollers toward and away from each other to apply successively increasing and decreasing transverse compression to the tube and the fin during such circumferential movement of said compression rollers.

6. Apparatus for shaping to non-circular section a circular section finned tube having a helical fin extending outwardly from its surface comprising at least one pair of spaced circumferentially slotted compression rollers, means for moving said rollers circumferentially around and relative to a finned tube with the rollers disposed at diametrically opposite points relative to the tube axis and the fin of the tube passing through the slots of the rollers, means for advancing the finned tube longitudinally in timed relation to the circumferential movement of said rollers, and means for successively moving said rollers toward and

away from each other as said rollers move circumferentially of the tube.

7. Apparatus for shaping to non-circular section a circular section finned tube having a helical fin extending outwardly from its surface comprising at least one pair of spaced circumferentially slotted compression rollers, means for moving said rollers circumferentially around and relative to a finned tube with the rollers disposed at diametrically opposite points relative to the tube axis and the fin of the tube passing through the slots of the rollers, means for advancing the finned tube longitudinally in timed relation to the circumferential movement of said rollers, and means operated in timed relation to the circumferential movement of said rollers for moving said rollers toward and away from each other as said rollers move circumferentially of the tube path.

8. Apparatus for shaping to non-circular section a circular section finned tube having a helical fin extending outwardly from its surface comprising at least one pair of spaced circumferentially slotted compression rollers, means for moving said rollers circumferentially around and relative to a finned tube with the rollers disposed at diametrically opposite points relative to the tube axis and the fin of the tube passing through the slots of the rollers, means for advancing the finned tube longitudinally in timed relation to the circumferential movement of said rollers, a cam extending circumferentially around the path of the tube adjacent said rollers and having diametrically opposite high and low points, and means engaging said cam for moving said rollers toward and away from each other as said rollers move circumferentially of the tube path.

9. Apparatus for shaping to non-circular section a circular section finned tube having a helical fin extending outwardly from its surface comprising a rotary head having an axial aperture therethrough, means for rotating said head about the axis of said aperture, at least one pair of spaced compression rollers mounted on said head on opposite sides of its axis of rotation and movable radially of such axis, means for advancing a tube longitudinally of said head aperture between said rollers, means for preventing rotation of a tube so advanced and stationary means adjacent said head for successively moving said rollers radially of said head toward and away from each other as said head rotates.

10. Apparatus for shaping to non-circular section a circular section finned tube having a helical fin extending outwardly from its surface comprising a rotary head having an axial aperture therethrough, means for rotating said head about the axis of said aperture, at least one pair of spaced compression rollers mounted on said head on opposite sides of its axis of rotation and movable radially of such axis, means for advancing a helically finned tube longitudinally through said head aperture between said rollers in timed relation with the rate of rotation of said head, means for preventing rotation of a tube so advanced, means for successively moving said rollers radially of said head toward and away from each other in timed relation to the rotation of said head, and means on said rollers for simultaneously compressively engaging the surface of a helical finned tube and the edge of a helical fin thereon.

11. Apparatus for shaping to non-circular section a circular section finned tube having a helical fin extending outwardly from its surface com-

prising a rotary head having an axial aperture therethrough, means for rotating said head about the axis of said aperture, at least one pair of spaced compression rollers mounted on said head on opposite sides of its axis of rotation and movable radially of such axis, means for advancing a helically finned tube longitudinally through said head aperture between said rollers in timed relation with the rate of rotation of said head, means for preventing rotation of a tube so advanced, means for successively moving said rollers radially of said head toward and away from each other in timed relation to the rotation of said head, and means on said rollers for simultaneously compressively engaging the surface of a helical finned tube and the edge of a fin thereon and for supporting the fin against movement longitudinally of the tube.

12. Apparatus for shaping to non-circular section a circular section finned tube having a helical fin extending outwardly from its surface comprising a rotary head having an axial aperture therethrough, means for rotating said head about the axis of said aperture, at least one pair of spaced compression rollers mounted on said head on opposite sides of its axis of rotation and movable radially of such axis, means for advancing a helically finned tube longitudinally through said head aperture between said rollers in timed relation with the rate of rotation of said head, means for preventing rotation of a tube so advanced, means for successively moving said rollers radially of said head toward and away from each other in timed relation to the rotation of said head, and a plurality of circumferential ridges and valleys on said rollers for respectively simultaneously compressively engaging the surface of a helically finned tube and the edge of the fin thereon, said ridges acting to support the fin against movement longitudinally of the tube.

13. Apparatus for shaping to non-circular section a circular section finned tube having a helical fin extending outwardly from its surface comprising a rotary head having an axial aperture therethrough, means for rotating said head about the axis of said aperture, at least one pair of spaced compression rollers mounted on said head on opposite sides of its axis of rotation and movable radially of such axis, means for advancing a helically finned tube longitudinally through said head aperture between said rollers in timed relation with the rate of rotation of said head, means for preventing rotation of a tube so advanced, means for successively moving said rollers radially of said head toward and away from each other in timed relation to the rotation of said head, and a plurality of circumferential ridges and valleys on said rollers of diameters that increase in the direction of the movement of said tube advancing means, said ridges and valleys acting respectively to compressively engage the surface of a helically finned tube and the edge of the fin thereon.
